UNITED STATES PATENT OFFICE.

FRED E. GILBERT, OF JACKSONVILLE, FLORIDA.

AUTOMATIC FUNNEL

1,023,012.

Specification of Letters Patent

Patented Apr. 9, 1912.

Application filed August 7, 1911. Serial No. 642,636.

To all whom it may concern:

Be it known that I, FRED E. GILBERT, a citizen of the United States, residing at Jacksonville, in the county of Duval and State of Florida, have invented certain new and useful Improvements in Automatic Funnels; and I do hereby declare the following to be a full, clear, and exact description of the invention, such as will enable others skilled in the art to which it appertains to make and use the same.

This invention relates to an improved automatic funnel and more particularly to that class of funnels in which the flow of the liquid issuing therefrom is automatically cut off through the liquid rising to a predetermined level in the receptacle to be filled.

The object of this invention is to provide an automatic funnel which is simple and durable in construction, arranged and constructed to retain the liquid in the bowl of the funnel after the liquid has been prevented from issuing from the nozzle of the funnel and one which will be cheap to manufacture.

To this end the invention consists of certain novel details of construction and combinations of parts as will be more fully hereinafter described and pointed out in the claims.

Reference is had to the accompanying drawings forming a part of this specification in which:

Figure 1 is a central vertical sectional view of the improved funnel, and; Fig. 2 is a detail view of the pipe connection to be used when liquid is forced under pressure through the nozzle of the funnel.

Similar reference characters indicate like parts throughout the several views.

1 indicates the bowl shaped body of the funnel preferably constructed of metal and is bent inwardly and downwardly at its upper edge to form a splash guard 2. Extending centrally and vertically of the bowl 1 is a hollow tube 3 closed at one end by a hollow cap 4, perforated at 5 to allow the liquid to pass freely from the bowl 1 into the tube 3 and is also perforated at 6 to allow the liquid to escape into any suitable receptacle being filled. The lower end of the tube 3 constitutes the nozzle of the funnel.

A rod 7 which is slidably mounted within the tube 3 carries on its upper end an indicating ball 8, and on its lower end a float 9,

and near the upper part of the rod 7 two wings 10 are mounted for engaging and releasing two retaining dogs 13 and 14. These dogs are pivotally hung from the hollow cap 4. The wings 10 extend outwardly and downwardly, are slotted as at 11 and 12 for receiving the pins 15 and 16 carried by the retaining dogs 13 and 14 and are adapted to throw the said dogs out of engagement with the valve mechanism as will be 65 hereinafter explained.

Encircling the rod 7, and slidably mounted thereon, is a valve stem 17 carrying the ball valves 18 and 19, the latter being somewhat smaller in diameter than the former. 70 The stem 17 also carries on the end opposite the valve 18 a cone shaped head 20 which is adapted to be engaged and held by the retaining dogs 13 and 14 while the valve stem is in its raised position.

Located within the tube 3 are valve seats 21, 22 and 23, the seats 21 and 23 being adapted to seat valves 18 and 19 when the liquid supply to the nozzle has been cut off and the seat 22 being adapted to seat the 80 valve 18 while the receptacle is being filled. It will thus be seen that while the valve 18 is in the position shown in Fig. 1 (filling position) no liquid can be forced out through the top of the tube 3, but will have a free 85 passage through the ports 5 and 6 into the receptacle to be filled. A string or wire 24 for resetting the valve 18, is attached to the upper end of the valve stem 17 and passes out through the cap 4 and is provided at its 90 outer end with a ring 30.

To facilitate filling the receptacle to any predetermined level a split ring 25 is provided forming a stop and is adapted to be moved along the outside of the funnel nozzle. A bolt 26 and nut 27 holds the ring frictionally against the nozzle to prevent slipping.

In Fig. 2 is shown the pipe connection for feeding a liquid to the tube and nozzle 100 under pressure and comprises a pipe T having an annular recess 28 positioned directly over the ports 5 in the tube. A pipe 29 is connected to the pipe T being also positioned over the ports 5 and liquid entering 105 therethrough under pressure will travel around the annular recess 28 and enter the ports 5 without leakage to the atmosphere.

The funnel being ready for use and the ring 25 positioned on the nozzle, the same is 110

inserted into the filling opening of the bottle, tank or other receptacle and operates as follows:—The liquid is poured into the bowl 1, passes through the ports 5, down 5 through the ports 6 and into the receptacle. When the receptacle becomes nearly full the rising liquid causes the float 9 to rise, carrying with it the rod 7, the wings 10 and the indicator ball 8. The wings 10 being rigidly secured to the rod 7 causes the valve retaining dogs 13 and 14 to move away from the rod 7 through the medium of the slots 11 and 12 engaging the pins 15 and 16 carried by the said dogs. This movement 15 causes the dogs 13 and 14 to disengage the cone shaped head 20 of the valve stem 17 and allows the valves 18 and 19 to drop into the valve seats 21 and 23, the valve 18 preventing the liquid from entering the funnel 20 nozzle and the valve 19 preventing the liquid from entering the upper part of the tube 3. The funnel is now removed from the receptacle and the trapped liquid is released. To reset the mechanism the string 25 or wire 24 is pulled, thereby raising the valve stem until the dogs 13 and 14 engage under the cone head 20 when the valve 18 will have left its seat 23 and entered the valve seat 22, thus preventing the liquid 30 from forcing up into the tube 3. The upper portion of the tube 3 completely incloses the valve mechanism, as shown in Fig. 1, so as to prevent heavy liquids such as machine oil, molasses, syrups, etc., from contacting 35 the said valve mechanism and interfering with its successful operation. It will be obvious, therefore, that when the valves are in the raised position liquid can pass freely through the nozzle 3 (being prevented by 40 the valve 18 from entering the upper tube), but is prevented from passing to the nozzle or to the upper tube portion by the liquid in the bowl bearing on the valve 18, which tends to seat the valve 19 more firmly, when 45 the supply is cut off from the nozzle automatically.

It is evident that those skilled in the art may vary the details of construction and arrangement of parts without departing from 50 the spirit of the invention, and therefore I do not wish to be limited to such features except as may be required by the claims.

What I claim is:

1. An automatic funnel comprising a bowl, a tube providing a nozzle, valves preventing liquid having access to the upper part of said tube, one of said valves preventing liquid having access to said nozzle, and valve actuating means, substantially as described. 60

2. In an automatic funnel, the combination of a tube constituting a nozzle and provided with a plurality of ports, a float in said tube, a valve in said tube adapted to control said ports, a valve seat carried by 65 said tube located below said valve, a second valve seat in said tube above said valve, and a connection between said float and said valve, substantially as described.

3. In an automatic funnel, the combination of a tube constituting a nozzle and provided with a plurality of ports, a float in said tube, a valve in said tube adapted to control said ports, a valve seat carried by 70 said tube located below said valve, a second valve seat in said tube above said valve, a connection between said float and said valve, a third valve seat in said tube above 75 said second seat, and a valve coacting with said third seat, said valves when seated 80 adapted to prevent liquid from flowing either up or down, substantially as described.

4. In an automatic funnel, the combination of a tube constituting a nozzle and provided with a plurality of ports, a float in said tube, a valve in said tube adapted to control said ports, a valve seat carried by 85 said tube located below said valve, a second valve seat in said tube above said valve, a third valve seat in said tube above 90 said second seat, a second valve coacting with said third seat, a tube carrying said second valve and provided with a head, a catch adapted to contact with said head, an inclined wing 95 coacting with said catch, and connections between said wing and said float, substantially as described.

In testimony whereof, I affix my signature, in presence of two witnesses.

FRED E. GILBERT.
